[57] CLAIM

I claim the ornamental design for a combined flashlight, police baton and self-defense spray unit, as shown and described.

DESCRIPTION

FIG. 1 is an exploded perspective view of the combined flashlight, police baton and self-defense spray unit showing my new design;

FIG. 2 is a left side elevational view thereof, the right side elevational view being a mirror image of the view shown in this Figure;

FIG. 3 is a top plan view thereof;

FIG. 4 is a bottom plan view thereof;

FIG. 5 is a left end elevational view thereof; and,

FIG. 6 is a right end elevational view thereof.
